SIGNALING DEVICE

Horace N. Carver, Wichita, Kans.

Application March 8, 1938, Serial No. 194,662

1 Claim. (Cl. 88—78)

This invention relates to signaling devices and more particularly to a portable signal adapted to be conveniently placed on highways and similar thoroughfares for warning motorists and the like of obstructions on a highway.

It is ordinarily difficult for operators of vehicles such as loaded trucks to pull off the road when it becomes necessary to make repairs on the vehicles under their control. Should the motor of a truck fail or the tires need changing, the stalled or otherwise stationary vehicle creates a hazard on the road, not only to approaching motorists, but also to the truck operators and the property under their control.

It is the principal object of the present invention to provide a signal of the character commonly known as a "road flare" which is capable of reflecting and/or refracting light rays generated by the lights of approaching vehicles, back to approximately their source to warn the occupants of those vehicles of the presence of obstructions on roads.

Other important objects of the present invention are to provide a collapsible light reflecting and/or refracting signal of sturdy and durable construction capable of withstanding shocks and jars without damage to the signal; to so design the signal that it is difficult to tip over accidentally; to provide a housing for the reflector or reflecting element of the signal which also acts as a supporting standard therefor; to provide a compact and easily operable signal of a high degree of efficiency; to provide a protective mounting for the reflector or light refracting element of the signal; to provide for automatically exposing the reflector or light refracting element of the signal upon opening the reflector housing; to so arrange the parts of the reflector housing as to interlock the same when closed; and to provide improved parts and arrangements of parts making up a signaling device according to the present invention.

In accomplishing these and other objects of the present invention, I have provided improved details of structure, the preferred forms of which are illustrated in the accompanying drawing, wherein:

Fig. 1 is a perspective view of a signaling device embodying the features of the present invention showing the device in collapsed condition to facilitate the storage and transportation thereof.

Fig. 2 is a detail fragmentary perspective view of a portion of the signal housing, particularly illustrating the interlocking lugs and recesses thereof.

Fig. 3 is an end elevational view of the signaling

device, part of the housing being broken away to illustrate the relative position of the reflector therein.

Fig. 4 is a detail perspective view of the signaling device in opened operative condition.

Fig. 5 is a detail fragmentary vertical cross-section through the light reflecting and/or refracting element of the signaling device on the line 5—5, Fig. 4.

Fig. 6 is a view similar to Fig. 5, illustrating a modified form of reflector and/or refractor element.

Referring more in detail to the drawing:

The invention generally includes a two part cover or housing member 1, Fig. 1, forming an enclosing base or standard for a light reflecting and/or refracting signal element 2, Fig. 4, the housing member 1 and signal element 2 being interconnected in such a manner that the housing is adapted to enclose the signal for suitable storage, the housing when opened automatically raising the signal to operative position and forming a rigid standard for adequately supporting the signal to reflect and/or refract light rays in opposite directions back to approximately their respective sources of incidence.

In the present instance the housing members of a signaling device embodying this invention are shown to preferably include substantially duplicate plates 3 and 4 cast or otherwise suitably formed of substantially circular shape, each having a substantially continuous peripheral laterally turned flange 5 having spaced recesses 6 and 7 of different size extending into the body of each of the plates and each flange having a lug 8 and notch 9 adjacent the lug in substantially oppositely disposed relation to the recesses 6 and 7 of the respective plates.

The plates 3 and 4 are preferably thickened over a limited area as at 10 adjacent their recessed portions to form a bearing surface for adjacent ends of the plates when opened and a boss 11 is preferably formed integrally on each of the plates between the recesses, the boss extending outwardly relative to the peripheries of the plates. The bosses 11 are each provided with an outer face 12, preferably flush with the outer face of its plate and has a laterally extending rounded end 13 opposite the face 12 forming a substantially semi-circular lug at the inner end of each of the bosses.

The signal element 2 preferably comprises oppositely disposed plates 14 and 15 each preferably formed of colored rolled glass or similar substantially transparent material having suit-

able outer faces and preferably prismatic inner faces 16 for reflecting and/or refracting light rays impinging against the outer faces back approximate their source of incidence. Lustrous 5 backings 17 may if desired be provided on the prismatic backs of the signal plates 14 and 15 which not only serve the purpose of enhancing the reflecting properties of the signal plates, but also prevent the collection of dust in the pockets 10 formed at the junctures of the sides of the prisms thus rendering the signal effective over long periods of time.

The edges of the signal plates are mounted within mating frame members 18 and 19 which 15 are preferably of substantially circular or ring shape of a size adapting them for fitting within the flanges 5 of the housing plates. The frames preferably have concaved inner surfaces 20 and 21 provided with spaced alignable bosses 22 20 which, in practice, initiate at the edges 23 of the frame concavities in such a manner that they are adapted for engagement by a corresponding boss on the other frame. The bosses terminate short of the edges 23 of the frame concavities 25 to form seats for the peripheral edges of the signal plates 14 and 15. The outer side edges of the plates are arranged for engagement by the edges 23 and these edges of the frames secure 30 the plates in position. The signal plate frames may be secured together in a suitable manner as by the extension of fastening devices 24 through aligned apertures 25 in the bosses.

A portion of the periphery of each signal plate frame is preferably flattened as shown at 26, 35 Fig. 4, the portion 26 of the frame 19 being provided with outwardly extending bosses 27 and 28 having substantially squared outer corners. The bosses 27 and 28 are provided with apertures 29 adapted to be aligned with similar apertures 30 in the bosses 11 on the housing plates 40 to receive a suitable hinge pin 31 therein to hinge or pivot the housing plates onto and about the signal element.

As a matter of practice, the signal plates 14 and 45 15 are preferably spaced, as shown at 32, Fig. 5, and the outer edges of the plates are engaged in grooves 33 and 34 of a gasket 35 mounted in the signal plate frames for cushioning the signal plates relative to their support and thereby permitting 50 relatively rough treatment of the assembled devices without danger of breaking the signal plates. The space 32 between the reflectors may, if desired, be filled with a suitable plastic 35 or the like for additionally supporting 55 the signal plates. Separation of the signal plates effects an economy since if one of the signal plates is broken, the other may still be used, the gaskets and/or plastic material acting to hold the unbroken signal plate in its frame so 60 that the signaling device may be employed to warn approaching motorists from at least one direction.

Also as a matter of practice, the housing plates 65 are provided on their outer surfaces with bosses 36 spaced inwardly from the thickened portions of the plates to form bearing points for the devices when opened and to protect an identifying mark or the like, not shown, on the outer surfaces of the signaling devices. Instructive characters 36' may also be provided on the inner 70 faces of the housing plates for aiding an operator in the proper use of the signaling device.

The assembly and operation of a signaling device constructed as described is as follows:

75 A pair of the housing plates 3 and 4 are pref-

erably employed together in facing relation, that is, with the peripheral edges of the flanges 5 in abutting relation and with the lugs and recesses arranged in interlocking relation. Since the plates are similarly designed they may be oppositely disposed relative to each other in such a manner that the bosses 11 are positioned adjacent each other in side by side relation, as shown in Fig. 1, when one of the plates is superimposed upon the other plate. The flanges 5 of the housing plates space the body portions thereof sufficiently for receiving therewithin the signal plate frame members 18 and 19 which, after being equipped with the signal plates 14 and 15 mounted on the gasket 35 in spaced back to back relation, are fitted and secured together.

One of the outwardly extending bosses on the frame 2, for example the boss 28, is then mounted in the smaller recess 6 of one of the housing plates, the other boss 27 of the frame fitting on 20 the outside of the opposite housing plate boss and within the larger recess 7. The hinge pin 31 is then applied to the aligned apertures 29 and 30 in the bosses in such a manner that the housing plates may be hinged relative to each other and to the signal element supporting frames mounted within the housing plates.

Since the ends 13 of each of the housing plate bosses are rounded, when one of the housing plates is moved away from its mate, its movement is free until it approaches a vertical position. Continued movement of the housing plate beyond approximately ninety degrees effects movement of the signal element frame, through interengagement of the squared ends of the respective bosses thereof, to substantially vertical position, thus placing the signal element in effective condition to reflect and/or refract light rays from either side thereof in opposite directions back to approximately the sources of the 40 respective light rays.

In open condition, the housing plates are in substantially the same horizontal plane, i. e. 45 coplanar relationship and provide a standard of substantial area to rigidly support the reflector in erected condition, thus precluding accidental hinging of the signal element to closed condition.

It is apparent that the present device may be placed either in front of, at the side of, or behind a vehicle on a road and that either of the signal 50 plates may be faced toward either direction of approaching traffic on the highway to warn the occupants of vehicles of the presence of an obstruction on the highway.

Closing the signaling device is a very simple 55 matter and any intentional thrust applied to the signal element in either direction of hinging movement of the housing plates and signal element forces the signal element downwardly and carries with it one of the housing plates to position that housing plate in a vertical position, the moved housing plate ordinarily following the signal element to oppositely disposed horizontal position. The peripheral flange on the moved housing plate then abuts its mating flange on the 60 other housing plate and the signal element is thus effectively enclosed in the housing.

The signaling device may then be picked up and suitably stored until the next occasion for its use.

In Fig. 6 a modified form of signal plate is illustrated wherein 37 and 38 designate the plates proper which may be formed of glass, or the like, having substantially plane inner and outer faces. 39 designates one of a plurality of buttons having 75

light reflecting and/or refracting properties. The buttons 39 preferably comprise body portions inserted in apertures 40, which may be strategically arranged in the signal plates to form a legend, and have retaining flanges 41 adjacent the rear ends thereof to prevent the buttons from dropping out of the signal plates from the forward faces thereof. The rear ends of the buttons may if desired be concaved, as shown at 42, in order to enhance the reflecting and/or refracting qualities thereof.

In this instance, the buttons are mounted in the signal plates from the rear faces of the plates prior to mounting the plates in spaced relation 15 in the signal plate frames 43 and 44.

The construction, assembly and operation in the modified form of invention is, aside from the button type of reflecting and/or refracting element substantially similar to that of the preferred 20 form of invention.

The principal advantages of a signaling device embodying the features of the present invention are that it is strong, rigid, durable and will withstand rough treatment. The housing plates or 25 members may be very simply flipped open or closed to and from interlocked engagement to place the signal element in effective or enclosed condition.

Since the housing plates, when open, have bearing support on their outer surface bosses, the tendency of the outer ends of the plates is to gravitate downwardly, thus holding the signal element more rigidly in vertical, operative condition. 5

The device is very compact and may be conveniently stored in any type of vehicle. Light rays may be reflected and/or refracted from either side of the signal element. Further, 10 should one of the signal plates be broken, the other signal plate is still effective to warn approaching motorists of the presence of obstructions to thus protect lives and property.

What I claim and desire to secure by Letters 15 Patent is:

A road signal including a pair of mating housing members, a frame adapted to carry a signal element, and means hinging said frame and housing members relative to each other, said housing 20 members having engageable flanges forming with the housing members an enclosure for the frame, said flanges having duplicate oppositely arranged interengageable means respectively for locking the housing members relative to each other when 25 in closed condition.
